(57) **CLAIM**

The ornamental design for a tablet computer, as shown and described.

DESCRIPTION

FIG. 1 is a front perspective view of tablet computer showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view thereof, taken from portion 8 in FIG. 1;

FIG. 9 is an enlarged view thereof, taken from portion 9 in FIG. 1;

FIG. 10 is an enlarged view thereof, taken from portion 10 in FIG. 4;

FIG. 11 is an enlarged view thereof, taken from portion 11 in FIG. 6; and,

FIG. 12 is an enlarged view thereof, taken from portion 12 in FIG. 7.

The dash-dash broken lines in FIGS. 8-12 encircling a portion of the tablet computer depict the extent of the enlarged view and form no part of the claimed design. The broken lines in the drawings illustrate portions of the tablet computer that form no part of the claimed design.

1 Claim, 12 Drawing Sheets
